AUGUSTUS WILLIAM LOHMAN, SR., OF CHATTANOOGA, TENNESSEE,
AND JOHAN PRUIS, OF CHICAGO, ILLINOIS.

CLOSED CONDUIT FOR ELECTRIC RAILWAYS.

No. 813,101.

Specification of Letters Patent.

Patented Feb. 20, 1906.

Application filed March 22, 1905. Serial No. 251,385.

To all whom it may concern:

Be it known that we, AUGUSTUS WILLIAM LOHMAN, Sr., a citizen of the United States, residing at Chattanooga, in the county of Hamilton and State of Tennessee, and JOHAN PRUIS, a citizen of Germany, residing at Chicago, Illinois, have invented certain new and useful Improvements in Closed Conduits for Electric Railways, of which the following is a specification.

Our invention relates to so-called "under-ground systems," and has particular reference to normally closed conduits and open circuits therefor.

The objects of the invention are in general to provide in a new and improved manner for a normally "dead" trolley wire or wires and the energization thereof only in short lengths or car lengths and only at the moment when the car passes over each such length; to protect the trolley-wires by a simple arrangement of shutters or closing-plates against weather conditions, which ordinarily interfere with proper contact or conductivity; to greatly simplify and make more dependable the mechanism for opening and closing the slot-shutters; to obviate the use of special shutter-opening mechanisms, and thereby materially reduce cost of construction, and, particularly, to eliminate the danger of serious wrecks and violent jarring of shutters by providing a shutter which interposes no ends at right angles to the path of movement through the trolley-arm slot and which is moved out of the path of said arm gradually instead of suddenly, as in shutters heretofore constructed.

Our invention consists in the novel construction and combination of parts which attain the above-named objects and such other advantages as will be referred to hereinafter in detail, and particularly pointed out in the claims.

In the accompanying drawings, forming a part of this specification, Figure 1 is an end view of an electric conduit with our invention applied thereto and the shutters in their closed position. Fig. 2 is a sectional end view taken substantially on line X X of Fig. 4 with the addition of a portion of the trolley-arm and trolley and showing the shutters in their open position. Fig. 3 is a plan view of Fig. 1. Fig. 4 is a plan view of Fig. 2, the trolley-arm being shown by dotted lines and

the top of the conduit-arch broken away to better disclose the shutters and their operating mechanism. Fig. 5 is a central longitudinal section through a portion of the conduit, partly broken away, taken substantially on line Y Y of Fig. 2. Figs. 6, 7, and 8 are detail views.

Referring to the drawings, A A' represent the walls of the conduit B, secured to cross-beams or T-rails C by means of bolts 2, which pass through flanges 3, projecting from the lower edges of said walls. The cross-beams C support brackets D, which have base-plates 4, fastened by bolts 5. In each bracket D is an opening 6 for the insulated feed-wire 7, and in the top of each bracket are journaled, on pivots 8, curved arms E E', to which are bolted at 9 the shutters or closing-plates F F', which close the slot G for the trolley arm or hanger H. The shutters F F' are made in suitable lengths to be easily moved by the trolley-arm. Said arm is shown provided with wear-plates 10 10', which contact with the shutters, though any other suitable contacts may take the places of said plates, if desired. On the arms E E' are counter-weight-rods I I', carrying adjustable counter-weights J J', held by set-screws 11 11'. Said arms and rods therefore constitute levers fulcrumed at 8, and the force exerted upon said levers may be varied by adjusting the counterweights. On each arm E or E' is a lug 12, to which is bolted at 13 a bar of wood or other non-conducting material K, and on the upper end of said bar is bolted at 14 a bracket 15, supporting part of a trolley-wire section which contacts with the trolley 17 or 17'. Opposite opening 6 on one of the brackets D, which supports a lever E' and shutter F', is a lug 18, in which are holes 19 for bolts 20, that clamp arms 20 to said lug. The latter arms are composed of insulating material and carry a contact-plate 21, bolted fast at 22. The contact-plate is connected with the feed-wire 8 through a wire 23, spliced to the feed-wire at one end and having its opposite end fastened to the apertured ear 24 of the plate 21. On each arm E' is a bracket 25, consisting of a curved plate 26 and lugs 27, between which is clamped an insulating-arm carrying contacts 29, adapted to engage therebetween the contact-plate 21. Holes 30 in the curved plate 26 receive screws or bolts 31, having threaded engagement with

the arm E'. Connection between the trolley-wire 16 and feed-wire 8 is completed through an insulated wire 32, fastened at one end to contacts 29 by the binding-post 33 and at the opposite end to a plate 34, clamped between head of bolt 14 and bracket 15.

The meeting edges of the shutters F F', as shown in Figs. 3 and 4, follow a zigzag line, each shutter presenting an obtuse angle 10 whose sides cross from side to side of the slot G on gentle inclines and each shutter laps beyond the edges of the usual slot-irons or, in other words, beyond the edges of the slot G, so as to prevent the possibility of presenting an obstacle to the trolley-arm. The slot G is a straight line as compared with the opening between the shutters, and the sides of said slot support the trolley-arm when the latter moves the shutters. Several important objects are attained by this construction—namely, special opening devices traveling in advance and in the rear of the trolley-arm for the purpose of opening a passage therefor may be dispensed with, thereby 25 greatly simplifying the construction and eliminating part of the danger of inoperativeness; no abutting shutter ends are interposed in the path of the trolley-arm, as the latter never comes into contact with any 30 other portions of each shutter than its inclined edges f and f', because, as stated, the blunt ends of each shutter are always under the slot-irons, as shown clearly by dotted lines in Fig. 3; the opening of the shutters 35 is effected gradually, each shutter being moved continuously to its full-open position during the transit of the trolley-arm one-half the length of the shutter and then as gently or gradually closed; instead of the ends of 40 each shutter being interposed as a menace in the path of the arm said ends are arranged laterally of the path of movement of the arm, as shown by dotted lines in Fig. 3, and, so far as each individual shutter is concerned, it 45 leaves the slot wide open at its ends, the closure being effected by the apex of the angle formed by the opposite shutter, which, as shown, overlaps one-half of each of two opposite shutters. Another advantage gained 50 by this construction is that the increase in weight of the mass to be moved incidental to increase in the length of each shutter is at least partly compensated for by the greater obtuseness of the sides f f' of each shutter-angle. As the inclines presented by the sides f f' become less steep the greater effectiveness will be given the trolley-arm in wedging 55 the shutters apart.

As shown in Figs. 1 and 2, the walls A A' 60 of the conduit are arched and any dirt or foreign substance which may lodge between the lower edges of the slot G and the upper faces of the shutters cannot bind the walls of the conduit and shutters together to interfere 65 with the movement of the shutters. When

the latter are closed, the trolley-wire is swung to one side and out of perpendicular alignment with the slot, as shown in Fig. 1. The object of this is to protect the wire against drippings of moisture or dirt, which, especially in winter-time, are apt to coat the trolley-wire with ice, which will interfere with the circuit.

As shown in Fig. 5, the trolley-wire is made in sections 16, each section having its 75 ends curved downwardly to insure against their accidentally striking the trolley 17 or 17'. Two trolley-arms and trolleys are provided, so that while one trolley traverses the gap between wire sections 16 the other trolley will 80 keep the circuit between the car and feed-wire closed.

By proper adjustment of the weights J J' the shutters and weights may be balanced on their pivots 8 to such an extent as to swing 85 under light pressure against the inclined edges f or f'.

Other modifications may be made in the embodiment of our invention without departing from the spirit thereof, and we therefore do not wish to confine same to the specific construction herein shown and described.

Having thus described our invention, we claim as new and desire to secure by Letters 95 Patent—

1. The combination with the conduit opening or slot of shutters, each thereof having sides forming an angle, the sides of which extend from one side of said slot and meet at 100 the opposite side thereof.

2. The combination with the slot-opening to a conduit, of oppositely-disposed shutters, each said shutter having edges which form the sides of an obtuse triangle, the base of 105 which obtuse angle rests at one edge of said opening while the apex of said angle touches the opposite side of said opening.

3. The combination with a conduit opening or slot, of pivotally-mounted shutters the 110 edges of which meet diagonally across said slot in zigzag order and provide inclines along which the trolley-arm is adapted to move and thereby impart a gradual opening-and-closing movement to said shutters.

4. The combination with a conduit opening or slot, of shutters having inclined meeting edges which cross the slot or opening from side to side in two intersecting vertical planes, the edges of each shutter meeting the intersecting edges of two oppositely-disposed 120 shutters, for the purpose set forth.

5. The combination with a conduit slot or opening, of oppositely-disposed shutters, each 125 shutter extending across the full width of said slot or opening and having oppositely-inclined edges which meet parallel edges of abutting shutters.

6. The combination with a conduit slot or opening, of oppositely-disposed shutters 130

which meet on angular lines crossing said opening, said shutters having pivotal supports within said conduit, means tending to hold said shutters in their closed positions 5 and means for varying the force exerted upon said shutters to hold same in said closed positions.

7. The combination with an electric conduit, of centrally-arranged supports, curved 10 shutter-arms E, E' mounted to swing in opposite directions upon a common axis of rotation, a feed-wire, a trolley-wire and means for making and breaking electrical connection between said feed-wire and trolley-wire 15 by, respectively, the opening-and-closing movements of said shutter-arms.

8. The combination with a conduit having a slot or opening, of shutters arranged to swing in the arc of a circle toward and from 20 each other, all of said shutters having substantially a common axis of rotation and having only their side edges projecting into 25 said opening, the abutting ends of said shutters meeting diagonally across said opening when closed.

9. The combination with a conduit having an opening for the trolley pole or arm, of shutters arranged to swing in arcs of circles toward and from each other, said circles having 30 their centers on a single axial line the abutting ends of said shutters meeting at the sides of said opening, a feed-wire, a trolley-wire mounted to swing with said shutters, and contacts electrically connected with, respectively, 35 said feed-wire and trolley-wire, the trolley-wire contact being movable with said wire and shutters.

10. The combination with a conduit having an opening or slot for the trolley-arm, of 40 concentrically-pivoted shutters arranged to swing toward and from each other in the arcs of circles, said shutters mounted on curved levers pivoted within said conduit, each said lever having a counterweight-arm and a 45 counterweight slidably adjustable thereon, a feed-wire, contact-arms upon said levers, and

means for making and breaking the circuit through said contact-arms and feed-wire by the movements of said levers.

11. The combination with an electric conduit, of centrally-arranged supports D having openings 6 therethrough for the feed-wire, the feed-wire, counterweighted and concentrically pivoted shutter-levers E, E' and I, I', the shutters F, F', having inclined edges f, f', 55 mounted on said levers, the insulating-arms 28 secured to levers comprising members E' and I, the bars K also secured to said levers and supporting the trolley-wire 16, the insulating-arms 20 secured to said supports and 60 the contacts 21 and 29 operable by the movements of said levers.

12. The combination with the concentrically-pivoted arms E, E' and shutters F, F' of the radial arms K supporting pivotally the 65 trolley-wire sections 16, the radial arms I, I' adjustably weighted to swing arms E, E' and the shutters thereon, the oscillating contacts which move with said shutters and the stationary contacts connected to the feed-wire, 70 and the trolley-arms H and H' and trolleys arranged as shown and described.

13. The combination with a conduit having the slot G, of the concentrically-pivoted shutters F and F', the curved arms carrying 75 said shutters, the trolley-wire section carried by one series of said arms and movable therewith to place the trolley-wire in line with the trolley when the arm of the latter opens said slot, the weighted arms and the adjustable 80 weights thereupon, the feed-wire, and the connections between said feed-wire and trolley-wire arranged to break the circuit therebetween when said slot is closed.

In testimony whereof we have hereunto 85 set our hands in the presence of two subscribing witnesses.
